JOSEPH C. GROFF, OF ALLENTOWN, PENNSYLVANIA

FUEL SUPPLYING AND INJECTING PUMP FOR INTERNAL-COMBUSTION ENGINES OF THE FUEL-INJECTION TYPE

Original application filed April 26, 1927, Serial No. 186,642. Divided and this application filed April 6, 1928. Serial No. 267,983.

The present invention relates to improvements in fuel supplying and injecting pumps for internal combustion engines of the fuel-injection type, and more particularly to pumps of this class which effect supply and the so-called airless injection of fuel to engines of this class which must operate over a wide range of running speeds.

The present application constitutes a division of my original co-pending application, Serial No. 186,642, filed April 26, 1927.

Heretofore, difficulty has been experienced in providing a fuel supplying and injecting pump which would in itself be capable of effecting desirable adjustments in the rate at which the fuel is delivered to the engine thereby without employing pumping mechanisms of complicated nature.

Accordingly, the present invention has for its objects the provision of a fuel pumping means of simple construction which will be adapted to adjustably control the rate at which it delivers fuel to the engine irrespective of its running speed.

Other and more detailed objects and advantages of the present invention will be hereinafter pointed out in the accompanying specification and claims and shown in the drawings, which, by way of illustration, show preferred embodiments of my invention.

In the drawings:

Fig. 1 shows a lateral cross-sectional view of a two-cycle port-scavenged internal combustion engine as illustratively arranged to operate my novel fuel pumping device which is shown in longitudinal cross-sectional view.

Fig. 2 shows a longitudinal cross-sectional view of a preferred alternative embodiment of my novel fuel-pumping device.

It should be understood that my fuel-pumping device may be applied as well to engines which operate upon the four-stroke cycle. This may be accomplished with only the usual slight modifications of known character which are involved with the requirement that the pump operate only half as fast as the engine shaft. However, for the sake of simplifying the description of my invention reference will be made hereinafter to

the operation of my pump in conjunction with an engine of the two-stroke type.

Referring now to Fig. 1, liquid fuel is supplied to the pumping chamber adjacent to the pumping plunger 12 through supply pipe 11 and via valve 16. Preferably, the fuel so supplied in pipe 11 should exist at some relatively low positive pressure in order to minimize any tendency for the pump to become "air-bound". The fuel might be so supplied from an overhead gravity tank or from a pump not shown in the drawings.

The amount of fuel delivered by the injection pump plunger 12 past the non-return discharge valve 13 and to the fuel injector 14 via delivery pipe 15 may be controlled in any desirable known manner. Preferably, however, the amount of fuel so delivered is regulated in accordance with the load demand by changing the period of time during which the suction-bypass valve 47 is closed downwardly on its seat 16. This may be accomplished in any suitable known manner not pertinent to the present invention and therefore means for doing so are not shown in the drawings.

Here it should be stated that the fuel injector 14, which is shown mounted in the wall portion 25 adjacent the combustion space 24, is of the automatic so-called airless injection type in that the fuel is injected directly into the combustion space 24 by and upon fuel-pumping action of plunger 12. That is to say, the rate at which the fuel is so injected into the combustion space via injector 14 is solely dependent upon the rate of fuel-pumping movement of said plunger 12.

According to the present invention, the fuel-pumping plunger 12 is given reciprocating movements the rate of which may be adjustably varied as may be desired. Thus, in Fig. 1, a pivotally mounted linklike member 28 is adapted to be oscillated about its fulcrum point 29 by any suitable driving means such as linklike member 27 which in turn is operated by the crank or eccentric like member 41. The linklike member 28 is also adapted to engage and bear upon another linklike member 34 at the pivotal joint 38. The other end of said linklike member 34 is connected, also piv-

totally, to plunger 12 and to guided crosshead member 36 which may be of any suitable known character.

The aforementioned fulcrum or pivoting point 29 is adapted to be adjusted laterally with respect to the line of reciprocatory travel of plunger 12 and driving link 34 by means of the suspending arm 30. The suspending arm 30 is itself adapted to pivot about its stationary fulcrum point 31 and to also engage the notched control quadrant 32.

Pivoting adjustments of arm 30 change the vertical position of the slotted-out portion of link 28 and causes lengthening or shortening 15 of the distance between the operating joints 29 and 38 to respectively effect quicker or slower rates of reciprocatory movement of the operatively bearing joint 38. That is to say, since without such change the pump 20 speed varies directly with the speed of the engine which drives it, the arm 30 would be in the position shown by line 33 for the slowest running speed, in its full line position for full running speed, and intermediate 25 positions for intermediate running speeds. By so doing the rate at which fuel is delivered by the pump to the fuel injector 14 may be maintained substantially unchanged irrespective of the running speed of the engine, if so desired.

The connecting linklike member 34 is adapted not merely to drive the fuel plunger 12 at various desirable velocities, but also, to prevent its imparting lateral forces to said 35 plunger. This is accomplished by the oscillatable supporting link 35 near the bearing joint 38 and by the aforementioned crosshead 36 at the point of connection with plunger 12.

In Fig. 1, to simplify the diagrammatic illustration of the fuel pumping linkage in order to more clearly show the interrelation of the different parts thereof, the above mentioned supporting link 35 is shown as being jointed to the connecting link 34 at a point between the driving joint 38 and the crosshead 45 36. However, in practice I prefer to move said point of connection between links 34 and 35 to the left of bearing joint 38; and also, to locate the fulcrum joint 52 of supporting link 50 35 somewhere above link 34 such as at joint 31 as is shown in Fig. 2. By so doing, there will result a desirable reduction in friction and wear at the various joints and particularly at the bearing joint 38.

In Figs. 1 and 2 the similarly acting parts bear the same reference characters only in Fig. 2 said parts also bear the letter "a" as a suffix.

It should be understood that the fuel plunger 12 requires the exertion of considerable force upon it to effect its purpose, and this force must naturally be transmitted through the driving linkage by means of the various aforementioned joints therebetween. Thus, 65 it becomes desirable, if not essential, to limit

not merely the number of the component links, but also, to minimize the extent of movements therebetween and at the different respective connecting joints.

It is of importance to note that the respective dead-center positions of the power piston's crank 39 and of the fuel pump driving cranklike means 41 are out of phase by substantially 90-crank degrees. With this construction, the fuel pump plunger 12 is 70 adapted to produce a substantially uniform rate of fuel delivery to the fuel injector 14 since the pumping action necessary to effect injection of the fuel thus takes place only during a comparatively small portion of the 80 time during which crank 41 is passing through the vicinity of its mid-stroke position. That is to say, the aforesaid mid-stroke position of crank 41 is thus made to substantially coincide with the top dead center position of the power crank 39, viz, with the corresponding range of fuel supply and/or injection.

What I claim is:

1. A fuel supplying and injecting system 90 for internal combustion engines of the fuel-injection type or the like, comprising in combination with driving means, and with valving, supply duct and injection nozzle means, a fuel pumping means comprising a link pivotally suspended from an arm, said driving means being adapted to oscillate said link about said point of suspension, a fuel pumping plunger, guided link means intermediate said oscillating link and said plunger, said 95 guided link means being operatively connected to said plunger and adapted to engage a bearing portion of said first named link and to be given reciprocating movement thereby, said suspending arm being adapted to adjust 100 the position of said point of suspension with respect to the path of said reciprocation, whereby said guided link and said plunger are adapted to produce desirable rates of fuel delivery to said injection nozzle irrespective 110 of the speed of the engine.

2. A fuel supplying and injecting system 115 for internal combustion engines of the fuel-injection type or the like, comprising in combination with driving means, and with valving, supply duct and injection nozzle means, a fuel pumping means comprising a link pivotally suspended from an arm, said driving means being adapted to oscillate said link about said point of suspension, a fuel pumping plunger, guided link means intermediate 120 said oscillating link and said plunger, said guided link means being operatively connected to said plunger and adapted to engage a slotted-out portion of said first named link and to be given reciprocating movement thereby, said suspending arm being adapted 125 to adjust the position of said point of suspension laterally with respect to the path of said 130

reciprocation, whereby said guided link and said plunger are adapted to produce desirably adjustable rates of fuel delivery to said injection nozzle irrespective of the speed of the engine.

6 In testimony whereof I hereto affix my signature.
